UNITED STATES PATENT OFFICE

ANDREW ROHALY, OF HARDIEVILLE, ALBERTA, CANADA

RAILWAY-CROSSING GATE

Application filed September 16, 1929, Serial No. 393,035, and in Canada July 20, 1929.

This present invention relates to certain new and useful improvements in a railway crossing gate.

The primary object of the invention resides in the provision of a railway crossing gate which will be positively operated by a locomotive or the like approaching the crossing from either direction.

Another object of the invention resides in the provision of a railway horizontally swinging crossing gate of the character stated which will be automatically closed as the locomotive or the like approaches the crossing from either direction and again automatically opened as the locomotive leaves the crossing, travelling from the same in either direction along the track.

A further object of the invention resides in the provision of a railway horizontally crossing gate of the character stated which will be automatically actuated by means carried by the locomotive to actuate controlling mechanism located along the track at either side of the crossing.

A still further object of the invention resides in the provision of a railway crossing gate of the character stated in which horizontally swinging gate for the opposite approaches to the crossing will be operated simultaneously and horizontally swung to closed or opened position in a positive manner as the locomotive approaches and moves away from the crossing.

The invention has for a still further object the provision of a railway crossing gate of the character stated which is of extremely simple and inexpensive construction and operation as well as highly efficient and accurate and completely automatic in its operation.

The invention has for a still further object the provision of a railway crossing gate of the character stated which may be installed at small cost and maintained in efficient operation at the minimum expenditure of time, labour or money, thus providing a proposition which is extremely attractive to railway companies, government officials and the public in general.

To the accomplishment of these and related objects as shall become apparent as the de-

scription proceeds my invention resides in the construction, combination and arrangement of parts as shall be hereinafter more fully described, illustrated in the accompanying drawings and pointed out in the claims hereunto appended.

The invention will be best understood and can be more clearly described when reference is had to the drawings forming a part of this disclosure, wherein like characters indicate like parts throughout the several views.

In the drawings:

Figure 1 is a plan view, showing the arrangement of the railway crossing gate with the horizontally swinging gate members in open position and a locomotive approaching the crossing;

Figure 2 is a view similar to Figure 1, showing the horizontally swinging gate members in closed position and a locomotive ready to move away from the crossing and cause automatic opening of the gate members;

Figure 3 is a vertical transverse section, taken substantially on the plane of line 3-3 of Figure 1, looking in the direction indicated by the arrows; and

Figure 4 is a detail transverse section, showing the actuating means, carried by the locomotive for actuating the fulcrumed control members for the gate operating mechanism.

Referring more in detail to the drawings, it is to be noted that a transverse control rod 6 is carried by the locomotive or the like, with a control roller 7 rotatably carried at either end thereof, outwardly of the main rails 8 of the track and above the same. As the locomotive approaches the crossing, the roller 8 at one end engages and rides on the reversely bevelled inner side wall or face 9 of the elongated actuating bar 10 which is located at the side of the track and mounted intermediate its ends on the upstanding fulcrum bolt 11. This wall or face 9 of the bar 10 is bevelled outwardly from its centre toward its opposite end, thus providing a bar 10 which constantly increases in width from its centre toward its opposite end, although its outer side wall or face is straight and in a plane parallel to the plane of the longitudinal axis of the bar 10. Connected to the

ears 12 on the end of the bar 10 nearer to the railway crossing 13, is one end of the flexible cable 14, which extends around guide rollers 15 arranged adjacent the side of the 5 track and then connects with the main sectional cable 16 which extends and is attached to large pulley wheel 17 on the upstanding shaft 18 for one of the horizontally swinging gate members 19, which latter are arranged at either approach to the railway 10 crossing. The horizontally swinging gate members 19 are arranged at opposite sides of the track, adjacent the crossing 13 and each includes spaced depending flexible straps 15 so as to prevent injury to persons, animals or the like near the crossing when the horizontally swinging gate members 19 are closed. The upstanding shaft 18 for the horizontally swinging gate members 19 are connected by 20 the transverse connecting bar 21 having its opposite ends pivoted to the radially extended arms 22 provided near the bottom of the upstanding shafts 18. These upstanding shafts 18 extend through supporting and 25 bracing brackets 23 and have their lower ends rotatably mounted in appropriate bearings 24 within the housings 25 which also enclose the arms 22 of the upstanding standards 18. A transverse housing 26 is also provided 30 between the housings 25 to enclose and protect the connecting rod 21 for the upstanding shafts 18 of the horizontally swinging gate members 19. This housing 26 extends transversely beneath the track rails so as to prevent 35 interference with the travel of the rolling stock over the track. Extended from the remaining or outer ends of the bars 10, are ears 27 with which are connected the flexible cables 28 passed around guide rollers 29 and 40 then connected and attached to the other or remaining end of the main flexible cables 16, opposite the farthest connection of the cables 14 with said flexible cable 16. It is thus apparent that the bars 10 operate together as 45 one is actuated to either open or close the horizontally swinging gate members 19, according to the movement and direction of travel of the locomotive or other member carrying the control bar 6, with respect to the 50 crossing 13.

As the construction of the device has thus been described in detail, brief reference is now had to its use and modus operandi: The actuating bars 10 are normally in the position shown in Figure 1, that is with the ends nearest the crossing 13 located near the side of the track while their opposite or outer ends are in their outermost positions with respect to the side of the track. Thus, a locomotive 55 approaching the crossing from either direction will move toward the crossing until the roller 8 on that end of the control rod 7 directed toward the side of the track on which the actuating bars 10 are located reaches a 60 position opposite the fulcrumed centre of 65

the first actuating bar 10. The roller 8 will then act upon the other half of the bevelled face 9 or of said actuating bar 10 and force the same outwardly, turning the actuating bar 10 on its fulcrum bolt 11. This causes 70 actuation of the cable 14 connected to said ends of the actuating bar 10 and results in operation of the main flexible cable 16 and all of the other cables 14 and 28 connected therewith, as well as compelling rotation of 75 the upstanding shafts 18 for swinging the gate members 19 horizontally toward the sides of the track to close said gate members 19. Thus, it will be seen that both of the gate members 19 will be automatically swung 80 horizontally to closed position in unison and the actuating bars 10 will also be correspondingly operated to reverse the position of the inclined end portion thereof. As the locomotive continues its movement and crosses the crossing 18 and moves away from the same, the roller 8 will in turn pass the outwardly swung end of the other actuating bar 10 and then operate upon the remaining end or half of the second actuating bar 10 85 to swing the second actuating bar 10 in a reverse direction on its fulcrum bolt 11. This results in the returning of all the cables 14 and 28 together with the main sectional cables 16 to their normal positions, thus reversing the rotation of the upstanding standards 18 and the horizontal swinging of the gate members 19 and reopening the latter, in unison. The operation is entirely automatic and the horizontally swinging gate members 19 will be closed in unison as a 90 train approaches from either direction and then automatically opened in unison as the train leaves the crossing and moves either way from the same. Owing to the control bar 7 having a roller 8 at either end, the roller 8 at one end functions when the locomotive is moving in one direction on the track and the roller 8 at the other end of the control bar 7 functions when the locomotive moves 95 in the other direction on the track, that is, when the locomotive is turned around or reversed in its position with respect to the crossing 13. It is also to be noted that no electrical current or other power is required 100 for the railway crossing gates when they are not being operated.

From the foregoing description taken in connection with the accompanying drawings, it will be manifest that a railway crossing gate is provided that will fulfill all the necessary requirements of such a device but as many changes could be made in the above description and many apparently widely different embodiments of my invention may be constructed within the scope of the appended claims without departing from the spirit or scope thereof, it is intended that all matters contained in the said accompanying specification and drawings, shall be inter- 110 115 120 125 130

preted as illustrative and not in a limited sense.

Having thus described my invention, what I claim as new and desire to secure by Letters Patent is:—

5 1. A railway crossing gate including horizontal swinging gate members each composed of a horizontal bar and flexible straps depending in spaced relation therefrom; rotatable upstanding shafts having limited rotation in either direction and each supporting thereon an end of the horizontal bar of one of said gate members; link connections between the lower ends of said shafts to assure 10 operation of said shafts in unison in opposite directions; an elongated actuating bar arranged along the railway track to either side of the railway crossing; each of said elongated actuating bars having its edge facing 15 the railway track bevelled from each end inwardly toward the centre thereof, said actuating bars being fulcrumed at their central points; and flexible operating means connected with either end of each of said actuating bars and operatively connected with 20 one of said shafts to cause operation of the latter and horizontal swinging of said gate members toward the railway crossing and across the approaches thereto as a train approaches the crossing from either direction and reverse operation of said shafts and said gate members as the train leaves the crossing after passing over the same.

2. A railway crossing gate including a pair 35 of upstanding shafts arranged to the side of each approach to the railway crossing; a gate member mounted on the upper end of each of said shafts and including a horizontal arm and flexible straps depending from the latter in spaced relation; a link connection extending beneath the track between the lower ends of said shaft; said link connection being oppositely connected to the said shaft to cause a reverse movement of the latter; a 40 pulley wheel carried on the lower end of one of said shafts; a looped flexible member extending around and attached to said pulley wheel; the said looped flexible member having each end divided into a pair of branches 45 extended in arcuate directions along the railway track; and a pair of elongated actuating bars fulcrumed at their centres adjacent one side of the track and on opposite sides of the crossing; one branch of each of the ends of 50 said looped flexible member being attached to the end of one of the elongated actuating bars nearer to the crossing, while the other branch of each end of said looped flexible member being attached to the far end of one of said 55 elongated actuating bars; and guide means for the branches of the said looped flexible members.

In testimony whereof I hereunto affix my signature.

65 ANDREW ROHALY. [L.S.]
